ADJUSTABLE X-RAY CASSETTE HOLDER

Frank J. Miller, 12255 Auburn Road,
Chardon, Ohio 44024

Filed Apr. 2, 1975, Ser. No. 564,267

Term of patent 14 years

Int. Cl. D24—01

U.S. Cl. D83—1 H

FIG. 2

FIG. 3

FIG. 4

FIG. 5

FIG. 1 is a pictorial view taken from above and one end of an adjustable X-ray cassette holder formed in accordance with my new design;

FIG. 2 is an end view of the holder as viewed from the left-hand side of FIG. 1;

FIG. 3 is an opposite end view of the holder as viewed from the right-hand side of FIG. 1;

FIG. 4 is a side view of the holder as viewed from the right-hand side of FIG. 1;

FIG. 5 is an opposite side view of the holder as viewed from the left-hand side of FIG. 1; and

FIG. 6 is an exploded view of the holder shown in FIG. 1 taken from above and one end showing the relative positions of the components which comprise the holder.

I claim:

The ornamental design for an adjustable X-ray cassette holder, as shown.
